(21) Appl. No.: **29/552,968**

The ornamental design for a front bumper cover for automobiles, as shown and described.

(22) Filed: **Jan. 27, 2016**

(30) **Foreign Application Priority Data**

Jul. 31, 2015 (KR) 30-2015-0038515

DESCRIPTION

(51) **LOC (10) Cl.** **12-16**

FIG. 1 is a perspective view of a front bumper cover for automobiles according to the present invention.

(52) **U.S. Cl.**

FIG. 2 is a front view of the front bumper cover for automobiles of FIG. 1.

USPC **D12/169**

FIG. 3 is a rear view of the front bumper cover for automobiles of FIG. 1.

(58) **Field of Classification Search**

FIG. 4 is a left side view of the front bumper cover for automobiles of FIG. 1.

USPC D12/169, 216, 90-92, 86, 171, 196, 163;
293/102, 113, 115, 117, 120; 296/180.1,
296/180.2

FIG. 5 is a right side view of the front bumper cover for automobiles of FIG. 1.

CPC .. B60R 19/52; B60R 2019/25; B62D 25/0845

FIG. 6 is a top view of the front bumper cover for automobiles of FIG. 1; and,

See application file for complete search history.

FIG. 7 is a bottom view of the front bumper cover for automobiles of FIG. 1.
